UNITED STATES PATENT OFFICE

153,952

DESIGN FOR A DESK OR SIMILAR ARTICLE

Clarence Karstadt, Glen Ellyn, and Charles M. Abrahamson, Aurora, Ill., assignors to All-Steel Equipment, Inc., a corporation of Illinois

Application December 28, 1946, Serial No. 135,830

Term of patent 14 years

(Cl. D33—7)

To all whom it may concern:

Be it known that we, Clarence Karstadt and Charles M. Abrahamson, both citizens of the United States of America, and residents of Glen Ellyn, county of DuPage, and State of Illinois, and Aurora, county of Kane, and State of Illinois, respectively, have invented a new, original, and ornamental Design for Desk or Similar Article, of which the following is a specification, reference being had to the accompanying drawings, forming a part thereof, wherein—

Figure 1 is a front elevational view of a desk embodying my design;

Figure 2 is a side elevational view of the same; and

Figure 3 is a rear elevational view of the same.

The present design is characterized by having downwardly tapered lines comprising downwardly tapered pedestals and downwardly tapered pontoon feet.

What we claim is:

The ornamental design for a desk or similar article, substantially as shown and described.

CLARENCE KARSTADT.

CHARLES M. ABRAHAMSON.
